OIL BATH INSULATOR

Robert Weill, Paris, France

Application January 27, 1931, Serial No. 511,573,
and in Germany January 27, 1930

1 Claim. (Cl. 173—318)

The protection of insulators of electric lines along the coast from salt spray is effected as is well known by the use of oil baths, the surface of the oil permitting of providing a satisfactory leakage line.

There have been used for this purpose insulators with petticoats curved inwards so as to form internal receptacles or basins. An increase in the leakage line in this case would be obtained 10 by a reduction in the internal diameter of the basin, but steps in this direction would quickly come to an end, since the basin would come too close to the axis of the insulator. Moreover, it is not always possible to make the internal 15 receptacles of sufficient number or of suitable dimensions in insulators having multiple petticoats having regard to the small space between such petticoats.

The insulator forming the subject of this invention permits of forming oil baths in the insulators having multiple petticoats and of doubling the leakage line obtained by the type of insulator in question. It is characterized in this that the petticoats are curved inwards in such manner 25 as to constitute external receptacles protected by caps against the weather, these receptacles being capable of being combined with internal receptacles.

The accompanying drawing illustrates half in 30 elevation and half in section a construction in accordance with the invention. The insulator support shown comprises three petticoats *a*, *b*, *c* of generally known arrangement. The upper petticoat *a* is curved inwards towards the upper 35 end so as to constitute an external receptacle *d* protected by the cap *e* fixed to a petticoat of the element above that shown.

This receptacle may be of metal which would simplify the construction without reducing enormously its function as an insulator. It is known in fact that only the oil ensures protection against surface discharges because the insulating surfaces 60 not covered with oil are rendered conductive by the salt deposits.

Such an arrangement is obtained by the receptacle *f* fitting the petticoat *b*. This receptacle is combined with an internal receptacle *g* and 65 constitutes a channel fitting astride the cover. The total leakage line to the surface of the oil is thus double that of the internal receptacle. It will be seen, moreover, that the radial dimensions 70 of the latter cannot be increased because of its proximity to the supporting ferrule *h*. The receptacles *f*, *g* are protected against deposits from the atmosphere by the cap *i*. To their common base is fixed a cap *j* intended to protect the receptacle of the upper petticoat of the following 75 insulator which is not shown in the drawing.

The arrangement described has the advantage 80 of being applicable to any known type of petticoat insulator, of increasing the efficiency of the oil baths and of being simple in construction.

Having now particularly described and ascertained the nature of my said invention and in what manner the same is to be performed, I declare that what I claim is:

In a petticoat insulator, an oil bath straddling 85 said petticoat, said bath being secured to the lower edge of the petticoat in order to be supported by the bottom only and in contact with said petticoat at this point only.
